UNITED STATES PATENT OFFICE.

ALVEDA GJERTSEN HOBART, OF MINNEAPOLIS, MINNESOTA.

COMBINATION TABLE AND IRONING-BOARD.

1,176,059.

Specification of Letters Patent. Patented Mar. 21, 1916.

Application filed July 24, 1915. Serial No. 41,705.

To all whom it may concern:

Be it known that I, ALVEDA GJERTSEN HOBART, a citizen of the United States, residing at Minneapolis, in the county of Hennepin and State of Minnesota, have invented certain new and useful Improvements in Combination Tables and Ironing-Boards, of which the following is a specification, reference being had to the accompanying drawings.

My present invention relates broadly to new and useful improvements in kitchen tables and as its principal object aims to provide an article of this character which is so constructed that an ironing board of the ordinary type, as well as one of the sleeve type may be supported below the top of the table during the ordinary use of the same.

Another object of the invention is to so construct the table that the top leaves thereof may be readily lifted into folded position so that the transverse end bars of the table may serve as supports for the ironing board, which is normally supported in the table below the top leaves thereof.

Another object of the invention is to provide an ironing board of the sleeve type which is slidably and pivotally attached to the lower face of one of the leaves, whereby it may be drawn out and then swung into horizontal position when it is to be used or pushed in to lie beneath the leaf to which it is attached when not in use.

The above, and other incidental objects of a similar nature, which will be hereinafter more specifically treated are accomplished by such means as are illustrated in the accompanying drawings, described in the following specification, and then more particularly pointed out in the claims which are appended hereto, and form part of this application.

With reference to the drawings, wherein there has been illustrated the preferred embodiment of this invention, as it is reduced to practice, and throughout the several views of which similar reference numerals designate corresponding parts, Figure 1 is a top plan view, showing the movable leaf of the table top turned back, and the two ironing boards in position for use; Fig. 2 is a view partly in section and partly in elevation of the table with the movable hinged leaf of

the table top turned back and the two ironing boards in the position, in the table, 55 which they assume when not in use; and Fig. 3 is a transverse section taken through the table in a vertical plane, disclosing the table ready for use.

In the embodiment of my invention shown 60 in the accompanying drawings, the table includes four corner legs 10, 11, 12 and 13, which are connected by a pair of end bars 14 and 15, and a longitudinal bar 16, which is disposed at the back of the table. On the 65 inner faces of the end bars and adjacent the lower faces thereof, are bolted, nailed or otherwise secured, the horizontal bars or strips 17, which members constitute supporting shelves or ledges for the ironing board, 70 generally designated by the numeral 18.

The top of the table preferably consists in two leaves 19 and 20, which members are connected to each other by hinges 21'. The leaf 19 is secured by nails or equivalent fastening devices upon the end bars 14 and 15 and the longitudinal bars 16. The leaf 20 is, however, free with respect to the end bars so that it may be swung to folded position, wherein it lies upon the leaf 19. From 80 the lower face of the leaf 20 and at the outer edge thereof depends a facing board 21, which member is adapted to be disposed between legs 10 and 11, as in Fig. 3 when the member 20 is in position upon the end bars. 85

From the foregoing description, it will be readily observed that the table itself is extremely simple in construction and that one of the leaves may be disposed to complete the top of the table or may be swung to lie 90 upon the other leaf, as in Fig. 1.

The ironing board, heretofore generally designated by the numeral 18, is formed in two sections 22 and 23, which are united by hinges 24'. The section 22 is of a length 95 approximately equal to the distance between the end bars 13 and 14, so that its terminals will lie upon the supporting shelves 17, when the ironing board is not in use. Obviously, as shown in Fig. 2 the section 23 is 100 folded to lie upon the upper face of the section 22 when the ironing board is supported below the top of the table. As a means for rigidly maintaining the two sections of the ironing board in extended position when the 105 ironing board is to be used, I employ a metal

strip or bar 24. This member 24 is adapted to be passed through the U-shaped metal straps 25, which are screwed or otherwise suitably secured to the lower face of the ironing board. Preferably, I apply two of these straps to the section 22 and but one of them to the section 23. As a means for limiting the movement of the bar 24, when it is applied to the board, I employ a stop block 26, which is secured to the bottom face of the member 22. A notch indicated at 27 is formed in the upper edge of the end bar 14, to accommodate the member 24, when the ironing board is in use.

15 As has been hereinbefore explained, I provide in connection with the table, a sleeve ironing board which is, as indicated at 28 in Fig. 2 of the conventional type. This sleeve board is connected to the fixed leaf 19 of the 20 table top by means of a spindle 29, which is slidably and rotatably seated in a block 30. The member 29 extends a considerable distance beyond the side of the sleeve board, so that it will still seat in the block 30, when 25 the sleeve-board is drawn out into position for use, as in Fig. 1. As shown in this figure, the ironing board is swung, when it is to be used, into horizontal position, to rest upon the end bar 13, so that its terminal will 30 project beyond this member.

A square block or strip, indicated at 31 is secured to the lower face of the leaf 19 as in Fig. 2 and is arranged for engagement by the terminal of the sleeve board when this 35 member is disposed beneath the member 19. Obviously the block 31 serves to maintain the sleeve board in parallel spaced relation to the member 19. In reduction to practice, it has been found that the form of this invention illustrated in the drawings and referred to in the above description as the preferred embodiment, is the most efficient and practical; yet realizing that the conditions 40 concurrent with the adoption of this device will necessarily vary, it is desirable to emphasize the fact that various minor changes in the details of construction, proportion and arrangement of parts may be resorted to, when required, without sacrificing any of

the advantages of this invention, as defined 50 by the appended claims.

What is claimed, is:—

1. A table including a plurality of supporting legs, bars connecting the legs, a top comprising a leaf fixed upon the bars, and a leaf hinged to the fixed leaf and free with respect to the bars, a sleeve-board, a block secured to the lower face of the fixed leaf, a spindle extending laterally from the sleeve-board, said spindle being slidably and rotatably mounted in the block, whereby said sleeve-board may be disposed beneath the fixed leaf and within the perimetrical limits thereof, or may be drawn outwardly and then turned over to lie beyond the limits of the fixed leaf and to rest at its intermediate portion upon one of the bars.

2. In a table, a supporting frame, a top including a fixed leaf and a hinged leaf, and a sleeve board having a member slidably and rotatably engaged with the under face of the fixed leaf whereby when the hinged leaf is turned over upon the fixed leaf the sleeve board may be laterally shifted to a position beyond the inner edge of the fixed leaf and then rotated to a position in which one end of said board projects beyond the end of the fixed leaf and rests upon the frame.

3. In a table, a supporting frame, a top including a fixed leaf and a hinged leaf, a sleeve board slidably and rotatably secured to the lower face of the fixed leaf adjacent one end thereof and laterally slideable into a position beyond the inner edge of the fixed leaf whereby the board may be rotated into a position parallel to the fixed leaf and resting upon the frame, and a stop on the rear end of the board normally engaging the under side of the fixed leaf and supporting the board in a position beneath but parallel to the fixed leaf.

In testimony whereof I hereunto affix my signature in the presence of two witnesses.

MRS. ALVEDA GJERTSEN HOBART.
